United States Patent Office

Des. 176,864
Patented Feb. 7, 1956

176,864

BRACELET OR THE LIKE

Adolph Katz, Providence, R. I., assignor to Coro, Inc.,
New York, N. Y., a corporation of New York

Application September 9, 1955, Serial No. 37,861

Term of patent 7 years

(Cl. D45—7)

Fig. 1

Fig. 3

Fig. 2

Fig. 1 is a plan view of a bracelet or the like showing my new design.

Fig. 2 is an edge view thereof.

Fig. 3 is a side elevational view of the bracelet.

I claim:

The ornamental design for a bracelet or the like, substantially as shown.
